UNITED STATES PATENT OFFICE.

JOHN A. HAYES, OF PHILADELPHIA, PENNSYLVANIA.

STOPPER FOR BOTTLES.

SPECIFICATION forming part of Letters Patent No. 694,013, dated February 25, 1902.

Application filed August 25, 1899. Serial No. 728,433. (No model.)

To all whom it may concern:

Be it known that I, JOHN A. HAYES, of Philadelphia, in the county of Philadelphia and State of Pennsylvania, have invented certain 5 new and useful Improvements in Stoppers for Bottles, of which the following is a specification.

My invention relates to an improved construction of stopper for bottles, the same being so arranged as to be adaptable to the 10 necks of bottles of varying diameters and that when in position in the neck it will be positively held against accidental displacement, but may be readily and quickly re- 15 moved when desired.

The object of my invention is to produce a stopper of this character which shall be simple and inexpensive in construction and which shall be particularly effective in connection with bottles containing gaseous or 20 effervescent liquids, such liquids having heretofore been retained within the bottles by means of corks or stoppers, which in turn have been wired or otherwise fastened to prevent 25 their accidental removal.

My invention consists, substantially, of the combination with the neck of the bottle, the mouth of said bottle being formed with an internal tapering chamber whose diameter is 30 greater at the bottom than at the top, a flexible cork adapted to said chamber and having a central bore through which the liquid may pass, and a screw-stopper adapted to said bore, whereby when in position in the bottle 35 the same will be effectively sealed and the whole secured against accidental displacement.

My invention further consists of the novel features of construction and arrangement of 40 parts, all of which will be hereinafter fully described, and particularly pointed out in the appended claims.

Figure 1 represents a central section of a bottle, showing my improved stopper in position 45 therein. Fig. 2 represents a similar view showing the screw-stopper removed. Fig. 3 represents a transverse section taken on the line $\alpha\alpha$ of Fig. 1.

Similar reference-numerals indicate corresponding parts in all the figures of the drawings.

Referring to said drawings, 1 designates a

bottle the body portion of which may be of any desired shape or configuration, but the mouth thereof is provided with a chamber 3, 55 whose diameter at the bottom is slightly greater than at the top.

4 designates ribs which are formed in the chamber 3, said ribs following the inclination of the wall of the chamber 3 and terminating 60 at a shoulder 5, against which latter the lower end of a cork 6 abuts. The exterior of the cork is made to conform with the shape of the chamber 3 and is provided with grooves 65 adapted to the ribs 4, so that when it is in place therein it will be evident that it cannot be rotated or readily removed without the exertion of considerable force. As shown in the drawings, the cork is provided with a central bore 7, which is tapered and is adapted to 70 receive therein the threaded shank 8 of a stopper 9, which latter when in applied position serves to expand the cork, so as to make its exterior impinge the wall of the chamber 3, thus more securely keeping the same in position. The head of the stopper is scalloped 75 or milled and is of such shape as to be easily and firmly grasped by the fingers during the operation of inserting or removing the stopper. During such operation it will be evident that the ribs 4 above referred to will prevent a rotative movement of the cork 6.

In practice the cork 6, which, as before mentioned, is provided with grooves to correspond with the ribs 4, is forced into the chamber 3, where it shall permanently remain, and the lower end of said cork is rounded, as at 10, in order that the contents of the bottle may pass freely thereover into and through the central bore 7, as will be apparent. 90

Having thus described my invention, what I claim, and desire to secure by Letters Patent, is as follows:

1. A stopper for bottles, comprising a tapering cork, the diameter of which is greater 95 at the bottom than at the top, and being adapted to fit into a correspondingly-tapered chamber in the mouth of the bottle, said cork being provided with a central bore, the wall of which is tapered or disposed oppositely to the external taper of the cork, the said cork having an irregular external configuration, and a threaded stopper adapted to said bore.
2. A stopper for bottles comprising a ta-

pering cork having a plurality of external grooves, said cork being larger in diameter at the bottom than at the top and being adapted to fit a correspondingly-shaped chamber in the mouth of the bottle, said chamber being provided with ribs which enter said grooves in the cork and prevent rotative movement thereof, said cork being provided with a central bore, the wall of which is tapered or disposed oppositely to the external taper of the cork, and a threaded stopper adapted to the bore in said cork.

3. A stopper for bottles, comprising a tapering cork having a plurality of external grooves, said cork being larger in diameter at the bottom than at the top and being adapt-

ed to fit into a correspondingly-shaped chamber in the mouth of the bottle, said chamber being provided with ribs which enter said grooves in the cork and prevent rotative movement thereof, said cork being further provided with a central bore, the wall of which is tapered or disposed oppositely to the external taper of the cork and being rounded or flared at its lowermost extremity, and a threaded stopper adapted to the bore in said cork. 20 25

JOHN A. HAYES.
